Fig. 1.

Fig. 2.

Fig. 3.

A detailed technical cross-sectional diagram of a mechanical device, possibly a pump or valve assembly. The diagram shows a complex arrangement of internal parts, including a central vertical column, various plates, and a base. Numerous labels are present, such as '1' at the top left, '14' in the upper center, '23 25' on the left side, '19' in the middle left, '16' at the bottom left, '20' and '22' at the bottom center, and '17' on the right side. The entire assembly is shown within a rectangular frame with a hatched pattern.

UNITED STATES PATENT OFFICE

GEORGE F. VAN HORN, OF EVANSVILLE, INDIANA

ROAD INDICATOR

Application filed October 25, 1926. Serial No. 143,999.

The present invention relates to improvements in the driving means for vehicle road indicators having a movable band or ribbon, bearing indicia at different points of its length 5 representing different road conditions, objects, or locations which will be encountered as the vehicle advances, whereby the movable band or ribbon is more accurately coordinated with the driving means and is susceptible to 10 improved regulation of its rate of travel.

The novel features and combinations involved in my improved driving mechanism are hereinafter described and are recited in the appended claims.

15 In the accompanying drawings:

Figure 1, is a longitudinal section;

Fig. 2, is a front view, the top of the case being broken away and the tape or ribbon being removed;

20 Fig. 3, is a front view;

Fig. 4, is a cross section; and

Fig. 5, is a detail view showing the spool and part of the ribbon.

The mechanism is carried by a suitable box- 25 ing or casing 1, having a cover 2 provided with a window or sight opening 3 which is provided with a pane of glass or celluloid 4.

The cover 2 may be removed and for that purpose it is secured in any suitable manner 30 to the boxing 1.

While I do not limit the invention to the use of a tape or ribbon which bears the indicia, nevertheless a tape or ribbon is well adapted to carry out the invention, such tape 35 or ribbon appears at 5, being originally wound on a spool 6 which is suitably mounted so that it can be removed to make way for another spool or ribbon, it being understood that the tape or band 5 is unwound from the spool 40 6 as the automobile travels. The tape or ribbon 5 passes over rollers 7 and partly around a corrugated feed roller 8 and thence through a channel or guide-way 9 out through an opening 10 in the box or casing 1.

45 A pressure or tension roller 11, subject to any suitable spring tension, presses the tape or ribbon 5 against the corrugated feed roller 8 to insure a positive and even feed of the ribbon or tape in the direction indicated by 50 the arrows.

The feed roller 8 is driven by gears 12, counter-shaft 13, and gears 14, from a shaft 16 which carries a large bevel gear 16.

The gear 16 is driven by a pinion 17 carried by a shaft 18 which is suitably mounted. 55 The shaft 18 carries a suitable splined friction pinion 19 which turns the shaft 18 and may be slid along said shaft by an arm 20 having a slot and pin connection 21 with the collar that carries said pinion. The arm 20 60 is carried by a shaft 22 which has a handle 23 located on the outside of the casing 1. This handle may be moved to different positions and secured in any suitable manner to lock the pinion 19 in adjusted position at any de- 65 sired distance from the center of rotation of a driving friction disc 24 with which said pinion engages. By this means, the rate of rotation of the shaft 18 and hence of the feed roller 8 may be changed at will so that the 70 operation of the device may be synchronized with that of any rotating part of the automobile from which the device is driven. The disc 24 is driven by gearing 25 from a spindle 26 which may be connected, by flexible shaft- 75 ing or otherwise, to the speedometer shaft or to any shaft on the car. Of course, it is necessary to so set the pinion 19 that it will be timed to obtain the correct feed of the ribbon 5 so that the indications on the ribbon will 80 appear at the proper points as the car travels along the road.

The ribbon 5 bears any suitable indicia to indicate the objects of interest or the road conditions or the hazards which will be ap- 85 proached. For instance, I have illustrated a combined curve in the road and a railroad crossing at 27. These indications or symbols appear in succession on the tape or ribbon 5 and are successively displayed through the window 4, it being understood that the appliance is located on the instrument board or in any suitable position where it may be readily observed by the driver. The ap- 90 pliance can, however, be located where it may be observed by passengers.

It will be understood that the invention can be readily changed so that it will be utilized to acquaint passengers in an automobile or 95

bus with points of interest which are being approached.

As thus far described, the invention is adapted to indicate road conditions and will serve its purpose if the driver or other person who should observe the device does, in fact, observe it as the car travels along. However, as it is necessary for a driver to watch the road ahead and as it is desirable that dangerous conditions be emphasized and forcibly brought to the attention of the driver, I have provided visual and audible signals and the ribbon or tape 5 is utilized for the purpose of causing the closing of electrical circuits to said signals.

In order that the sight opening 3 and the tape 5 may be properly illuminated at night, there is provided an electric bulb 28 arranged to illuminate them. This light may be illuminated at night.

The special signals which are provided comprise one or more signal lights 29 suitably mounted in the casing which are arranged underneath the lenses 30. The lenses 30 may be of the same color or they may be of different colors or of any desired combination of colors. In fact, it is advantageous to have at least some of these lenses of a color representing danger, for instance amber or red. I do not restrict this part of the invention to any color or colors. I also provide one or more audible signals, for instance electric bells 31 which are energized to give audible warning when the ribbon or tape 5 displays the approach of a point of danger.

To enable the tape or ribbon 5 to automatically operate the lamps 29 and bells 31, said ribbon or tape is provided with slots 32. The slots 32 correspond in number with the lights 29, by preference, and they are arranged in offset relation to each other and are related to the indications 27 so that the appropriate lamp 29 will be illuminated when the bell 31 is sounded, to convey to the driver the particular condition being approached. For instance, a railroad crossing is perhaps the most dangerous condition to be encountered by the driver of a bus or automobile; consequently, it is advisable to arrange one of the slots 32 in such relationship to the indication 27 representing a crossing as will insure the illumination of one of the lights 29 representing danger, for instance, a light arranged to illuminate a red lens or an amber lens 30.

There are as many electrical switches 33 as there are signal lights 29. These switches are normally held open by the contact of the ribbon or tape 5 with an arm 33' thereof which operates the switch against the action of a spring 33" to open the contacts 33'". The arm 33' of each switch is arranged so that it will enter the appropriate slot 32 in the ribbon or tape 5 when said slot comes

into register therewith. When this occurs, the spring 33" closes the switch contacts 33'" and thus closes the circuit 34 to the appropriate lamp 29.

Preferably, the arm 33' has a roller so that it will operate easily when entering or leaving the slot 32.

The bell or bells 31 are sounded each time one of the switches 33 closes.

What I claim is:

1. In a road indicator for vehicles of the character provided with a feed roller and a movable band or ribbon driven thereby bearing indicia at different points of its length representing different road conditions, objects, or locations which will be encountered as the vehicle advances, positively and continuously acting driving means for said band or ribbon comprising a shaft adapted to be driven by the vehicle, a bevel pinion carried by said shaft, a rotatable flat friction disc which carries bevel gear teeth which mesh with the aforesaid pinion, whereby the disc is positively driven without possibility of slippage in respect to the aforesaid pinion, a friction pinion bearing against the friction face of said flat disc, and a train solely comprising rotary driving elements operated by said friction pinion which directly connects the friction pinion to the feed roller for the band or ribbon.

2. In a road indicator for vehicles of the character provided with a feed roller and a movable band or ribbon carried thereby bearing indicia at different points of its length representing different road conditions, objects, or locations which will be encountered as the vehicle advances, positively and continuously acting driving means for said band or ribbon comprising a shaft adapted to be driven by the vehicle, a bevel pinion carried by said shaft, a rotatable flat friction disc which carries bevel gear teeth which mesh with the aforesaid pinion, whereby the disc is positively driven without possibility of slippage in respect to the aforesaid pinion, a shaft arranged crosswise of the flat friction disc, a friction pinion slidably mounted on, and rotatable with, said last-named shaft and bearing against the friction face of said flat disc, whereby said friction pinion is driven by said disc, manually operable means for shifting said friction pinion along its shaft and holding it where set, thereby to enable the rate of travel of the band or ribbon to be regulated, and a train solely comprising rotary driving elements operated by said last-named shaft which directly connects said shaft to the feed roller for the band or ribbon.

In testimony whereof I affix my signature.
GEORGE F. VAN HORN.
